CLAIM

The ornamental design for a rotisserie frame, as shown.

DESCRIPTION

FIG. 1 is a perspective view showing my design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof.
FIG. 8 is a front elevational view of the rotisserie frame broken down for transport; and,
FIG. 9 is a perspective view of the rotisserie frame carrying a rotisserie spit and arranged on a grill.
The broken lines shown in the drawings are for illustrative purposes only and form no part of the claimed design.
